ATTORNEY

UNITED STATES PATENT OFFICE.

JOHN L. RITER, OF BROWNSVILLE, INDIANA.

SEEDING-MACHINE.

SPECIFICATION forming part of Letters Patent No. 274,518, dated March 27, 1883.

Application filed October 13, 1882. (No model.)

To all whom it may concern:

Be it known that I, JOHN L. RITER, of Brownsville, Union county, Indiana, have invented certain new and useful Improvements in Seeding-Machines, of which the following is a specification.

In the accompanying drawings, Figure 1 represents the seed-box of a seeding-machine, shown in rear elevation; Fig. 2, a vertical longitudinal section of the same at the seat of one of the seed-cups, and Fig. 3 a vertical transverse section at same point.

This invention relates to the means for attaching the series of seed-cups to the bottom of the seed-box, as hereinafter set forth.

A is the seed-box; B B, the end pieces of the seed-box; C and K, the sides of the seed-box; D, the bottom of the seed-box; E, the longitudinal shaft for operating the seed-wheels; F, the seed-cups to receive the seed-wheels; G, transverse grooves in the bottom of the seed-box, one at each seed-cup; H, a widened portion of the grooves at their tops, giving them a T form; I, flanges projecting from the sides of the seed-cups; J, the seed-wheels.

The seed-cups slide into the grooves, and are retained by the flanges in an obvious manner.

The cups may be adjusted transversely to the seed-box into true alignment with the shaft. 30 No skill is required to set the cups into alignment. No screws are required, and the grooves being susceptible of being machine-made, the device is much cheaper than the usual screwed attachment.

The grooves may be in dovetail form, and the flanges I constructed to suit.

Seeding-machines have been devised in which the seed-cups are partly supported by the projection of a rear flange in a grooved 40 piece beneath the seed-box, and also by means of flanges seating in dovetail sockets secured separately beneath the seed-box. I do not claim any such devices as of my invention.

I claim as my invention—

In a seeding-machine, the combination of a seed-wheel shaft, a series of seed-cups having side flanges, and a seed-box having a perforated wooden bottom provided with transverse grooves cut in its lower face to engage said side flanges and support the seed-cups, substantially as set forth.

JOHN L. RITER.
